ORNAMENTAL HEATING RADIATOR

Mikolaj Stefanczyk, Hamtramck, Mich.

Application April 11, 1936, Serial No. 73,942

6 Claims. (Cl. 257—124)

This invention relates to heating radiators for steam or hot water heating systems such as are commonly provided in homes and other buildings, and has more particular reference to a novel and highly ornamental radiator of this kind.

More particularly, the present invention contemplates the provision of an ornamental heating radiator for steam or hot water heating systems, essentially in the form of a statue of a bird or fowl having tail feathers, the body of the bird or fowl being of double wall construction to provide a jacket through which the heating medium may be circulated, and the tail feathers being in the form of hollow radiator sections secured in side by side relation and attached at corresponding ends to the tail end of the body so as to communicate with the jacket of the latter and thereby provide for circulation of the heating medium through such tail feather radiator sections.

A further object of the present invention is to provide an ornamental radiator of the above character which is extremely simple and durable in construction, and which is composed of parts which may be economically manufactured and readily assembled.

Other objects and features of the present invention will become apparent from the following description when considered in connection with the accompanying drawings, in which:

Figure 1 is an elevational view of an ornamental radiator constructed in accordance with the present invention, partly broken away and in section.

Figure 2 is a top plan view thereof.

Figure 3 is a fragmentary view of the same substantially in central vertical longitudinal section.

Figure 4 is a section on line 4—4 of Figure 1.

Figure 5 is a transverse section on line 5—5 of Figure 2.

Figure 6 is a front elevational view of a modified form of ornamental radiator constructed in accordance with the present invention.

Figure 7 is a section on line 7—7 of Figure 6; and

Figure 8 is an enlarged fragmentary vertical longitudinal section illustrating the manner of connecting the tail feather radiator sections to the tail end of the body in the construction of Figures 6 and 7.

Referring in detail to the drawings, the present ornamental radiator is preferably in the form of the statue of a peacock having a body 5, a head 6, wings 7, tail feathers 8, and legs 9, the bird being perched upon a suitable support 10 having cross bars at 11 clasped in the feet of the bird.

The body 5 is preferably of hollow form as shown more clearly in Figures 3 and 8 so as to be relatively light in weight, and is also of double wall construction to provide a jacket 12 through which the heating medium such as steam or hot water, may be circulated.

The head 6 is preferably of hollow form as shown more clearly in Figure 3, and provided with translucent eye members 13 in the form of properly colored pieces of glass, a suitable electric lamp 14 being arranged within the head 6 to be lighted for illuminating the eye members 13. The body 5 is preferably in the form of a metal casting having the upper end of its neck portion reduced and threaded for detachable reception of the head 6 which is in the nature of a separate casting. The wires for supplying current to the lamp 8 may be suitably led into the head 6.

The wings 7 are preferably in the form of separate plate-like castings attached to opposite sides of the body 5 by means of screws 15 or the like, said wings extending rearwardly so as to overlie the connections of the tail feather sections 8 with the tail end of the body 5 as will be apparent from the several views, thereby substantially concealing such connections from view.

The tail feather radiator sections 8 are in the form of elongated hollow castings which are tapered longitudinally in a lateral or transverse plane, being rigidly bolted in side by side contiguous relation by means of transverse tie bolts 16 extending through registered ears 17 of the sections 8 and having nuts 18 threaded on the ends thereof. The sections 8 preferably are devoid of any direct communication between the adjacent sides thereof, and are individually connected at their inner narrower ends with the tail end of the body 5 by means of unions 19 so as to provide communication between the interior of each section and the jacket 12 of the body 5. Two union connections 19 are provided for the inner end of each section 8 so as to facilitate circulation of the heating medium to the jacket 12 from the sections 8, or vice versa, depending upon the direction of circulation. The unions 19 afford rigid connections between the sections 8 and the body 5, and it is these connections which are substantially concealed from view by the wings 7 as above mentioned.

Suitable provision may be made for facilitating connection of pipes with the present radiator to provide for circulation of the heating medium through the jacket 12 and radiator sections 8, as requirements may dictate. As shown, the radi-

tor is provided with a nipple for one pipe connection with the jacket 12 at the lowermost point of the latter as indicated at 20. Other nipples or pipe connections may be suitably provided. 5 For instance, in the embodiment of Figures 1 and 2, each tail feather radiator section 8 is provided with a bottom pipe connecting nipple 21 so that the heating medium may be supplied to each individual section 8 or discharged from one 10 of the same, depending upon the direction of circulation.

In the form of the invention shown in Figures 1 and 2, the bird is represented as having its tail feathers bunched and lowered. For this purpose, 15 the sections 8 are comparatively few in number and relatively narrow, as well as extended rearwardly and downwardly to a point adjacent the floor or ground. In order to sustain the sections 8 in spaced relation to and above the floor or ground and prevent tilting of the radiator on the support 10, one of the sections 8 may be provided with an attached supporting leg 22.

In the embodiment of Figures 6 to 8 inclusive, 25 the bird is represented as having the tail feathers elevated or extended rearwardly and upwardly above the head 6', as well as in spread condition. For this purpose, the sections 8' are relatively wide and considerable in number, being extended almost directly upwardly from the tail end of 30 the body 5'. To provide for proper support and connection of the sections 8' with the body 5' in this form of the invention, the tail end of the body 5' is preferably provided with an inward offset 35 providing a substantially horizontal shoulder 23 and a substantially vertical wall 24, the lower smaller ends of the sections 8' being seated in this offset or recess upon the shoulder 23 and provided with the union connections 19' through the wall 24 and an opposed inwardly offset substantially vertical wall portion 25 of the adjacent 40 end of each section 8'. The statue in Figure 1 is posed so as to be suited for placing alongside a wall for being seen in side view when installed, while the radiator of Figure 6 provides the bird 45 posed for being placed with its back to the wall so as to be seen in front view when installed. To relieve the connections or unions 19' from strain due to the weight of the sections 8', the latter may be braced in position by a brace connection 26 between the lower end portion of one 50 of the sections 8' and a cross bar 11' of the perch or stand 10' at the rear of the body 5'.

Other than above described, the construction 55 of both forms of the invention is similar in all essential respects. In Figures 6, 7 and 8, the wings 7' are attached by screws 15', the body 5' has the jacket 12', both legs 9' are arranged so that the feet thereon grasp the front cross bar 11', and the sections 8' have ears 17' through 60 which the tie bolts 16' extend, nuts 18' being threaded on said tie bolt 16'. Obviously, the various parts may be readily cast in ornamental form to closely resemble the parts of the bird which they simulate.

65 It will be seen that I have provided a highly ornamental radiator which will be pleasing to the eye and well adapted to enhance its surrounding, as well as so constituted to effectively carry out the stated objects of the invention from an utilitarian standpoint. Minor changes in the detail construction and form of parts may be resorted to without departing from the spirit and scope 70 of the invention as claimed.

What I claim as new is:

75 1. A heating radiator of the character de-

scribed, comprising a statue of a bird having a body and tail feathers, said body being of double wall construction to provide a jacket through which a heating medium may be circulated, said tail feathers comprising a plurality of hollow elongated radiator sections secured together in side by side relation, means for rigidly connecting said tail feather sections at corresponding ends with the tail end of the body and for placing said tail feather sections in communication with said jacket, and means to facilitate connection of the supply pipe for a heating medium with the radiator.

2. A heating radiator of the character described, comprising a statue of a bird having a body and tail feathers, said body being of double wall construction to provide a jacket through which a heating medium may be circulated, said tail feathers comprising a plurality of hollow elongated radiator sections secured together in side by side relation, means for rigidly connecting said tail feather sections at corresponding ends with the tail end of the body and for placing said tail feather sections in communication with said jacket, means to facilitate connection of the supply pipe for a heating medium with the radiator, and wing-simulating plates attached to opposite sides of the body and overlying the connections between the tail feather sections and the body to substantially conceal said connections from view.

3. A heating radiator of the character described, comprising a statue of a bird having a body and tail feathers, said body being of double wall construction to provide a jacket through which a heating medium may be circulated, said tail feathers comprising a plurality of hollow elongated radiator sections secured together in side by side relation, means for rigidly connecting said tail feather sections at corresponding ends with the tail end of the body and for placing said tail feather sections in communication with said jacket, and means to facilitate connection of the supply pipe for a heating medium with the radiator, the connections between each tail feather section and the body consisting of two unions disposed one above the other.

4. A heating radiator of the character described, comprising a statue of a bird having a body and tail feathers, said body being constructed for circulation of a heating medium therethrough, said tail feathers comprising a plurality of hollow elongated radiator sections secured together in side by side relation, means for rigidly connecting said tail feather sections at corresponding ends with the tail end of the body and for placing said tail feather sections in communication with said body, and means to facilitate connection of the supply pipe for a heating medium with the radiator.

5. A heating radiator of the character described, comprising a statue of a bird having a body and tail feathers, said body being of double wall construction to provide a jacket through which a heating medium may be circulated, said tail feathers comprising a plurality of hollow elongated radiator sections secured together in side by side relation, means for rigidly connecting said tail feather sections at corresponding ends with the tail end of the body and for placing said tail feather sections in communication with said jacket, means to facilitate connection of the supply pipe for a heating medium with the radiator, the tail feather sections representing tail feathers in lowered bunched condition and

extending rearwardly and downwardly from the body, a floor engaging supporting leg carried by one of said tail feather sections, said body having leg members, and a support having cross bars clutched by the feet on said leg members.

6. A heating radiator of the character described, comprising a statue of a bird having a body and tail feathers, said body being of double wall construction to provide a jacket through which a heating medium may be circulated, said tail feathers comprising a plurality of hollow elongated radiator sections secured together in side by side relation, means for rigidly connecting said tail feather sections at corresponding ends with the tail end of the body and for plac-

ing said tail feather sections in communication with said jacket, and means to facilitate connection of the supply pipe for a heating medium with the radiator, said tail feather sections representing the tail feathers in raised and laterally spread condition and comprising longitudinally tapered sections extending substantially directly upward from the tail end of the body above the head of the bird, the tail end of the body having an inward offset providing a substantially vertical wall and a lower horizontal shoulder, the narrower ends of the tail feather sections being seated in said offset and upon said shoulder.

MIKOLAJ STEFANCZYK. 15
